UNITED STATES PATENT OFFICE.

ALOIS KLOSE, OF PORTLAND, OREGON.

BRICK-KILN.

1,160,987.

Specification of Letters Patent. Patented Nov. 16, 1915.

Application filed April 29, 1914. Serial No. 835,287.

To all whom it may concern:

Be it known that I, ALOIS KLOSE, a citizen of the United States, and a resident of Portland, county of Multnomah, State of Oregon, have invented a new and useful Improvement in Brick-Kilns, of which the following is a specification.

This invention relates to the construction of continuous brick kilns.

As commonly constructed, a brick kiln consists of a series of intercommunicating kiln chambers in which the bricks to be burned are piled. The firing of the chambers and the consequent burning of the bricks is done progressively. The difficulty encountered in these kilns is, the moisture laden vapors are not carried from the chambers with sufficient rapidity to the stack, but the vapors are permitted to remain in the chambers for such length of time that they will condense on the brick and have a tendency to discolor the latter.

One of the main objects of my invention, therefore, is to provide means for the rapid carrying of the vapors from the chambers to the stack. I accomplish this object by providing draft flues in the partition walls between the chambers, and connecting these flues with the chambers respectively and the stack.

Other objects of, and advantages obtained by my invention are fully set forth in the following detailed description of my invention.

In the accompanying drawings: Figure 1 is a side elevation of a portion of a brick kiln embodying my improvement; the draft openings for the different chambers are not shown; Fig. 2 is a plan view of the parts shown in Fig. 1; Fig. 3 is a longitudinal vertical section of the kiln taken approximately on the line indicated by the arrow 3 in Fig. 2; Fig. 4 is a view similar to Fig. 3, but taken on the line indicated by the arrow 4 in Fig. 2; Fig. 5 is a longitudinal horizontal section taken on the line 5 of Fig. 1; Fig. 6 is a transverse vertical section taken on the line 6 of Fig. 3, looking toward the left; Fig. 7 is a view similar to Fig. 6, but taken on the line 7 of Fig. 3; and Fig. 8 is a horizontal section taken on the line 8 in Fig. 4.

The kiln A comprises a series of arched burning chambers, a, separated by the partition walls b, in each of which walls is located a small opening c. These openings provide

direct communication between the burning chambers. The openings, c, in adjacent partition walls are located on opposite sides of the kiln. See Fig. 7. Each burning chamber, a, is provided with doors, d, in its opposite end walls, which doors form an entrance way through which the brick may be carried in and piled up in the chamber. The top of the kiln is provided with a number of parallel fuel openings e; e', which connect with the interior of the chambers, a, and form means for introducing the fuel into said chamber from the outside. The end walls of each chamber are provided with small openings f, located in the same vertical planes as the fuel openings e'. After the brick is piled in the kiln chambers, a, the wickets which seal the doorways are made with small openings g (represented by broken lines in Figs. 1, 3 and 4), such openings being located in the same vertical plane as the fuel openings e.

Extending longitudinally beneath the floor of the kiln are the main draft flues h connecting directly with a smoke-stack, not shown. In some instances I have found it advisable to install suction fans in these main flues for the purpose of establishing an induced draft therethrough.

Each wall of the kiln, at the points of junction with the partition walls b, is provided with vertical draft flues, i, the tops of which are enlarged as shown at j. The vertical flues, i, are arranged alternately on opposite sides of the kiln, and also at the end of the partition walls farthest from the openings c. Each partition wall b is provided with a longitudinal horizontal flue k connecting with the enlarged portion j of the vertical flue. Furthermore, each flue k is made with a number of lateral draft openings, m, which connect with the fuel openings e' (see Fig. 4) and thereby with the interior of the kiln. The enlarged portion j of the vertical flue, i, is provided with a lateral flue m', which also connects with the interior of the fuel chamber through the side walls. A damper n, operated from the top of the kiln by a handle n', controls the draft through the openings m and n. The fuel openings e, e' are provided, with caps r, which may be removed when fuel is being placed in the chamber, and the openings f, g are also closed except when it is desired to rake down the fuel.

The advantages of my construction over

all previous constructions are as follows: By making the openings, *c*, between the adjacent chambers, *a*, of small dimensions, they will be enabled to stand up under the 5 temperature stresses which develop in the partition walls. Furthermore, when the heated air is being induced from one chamber to another, it must pass down and through the openings *c*, and hence will circulate through the lowest courses of the 10 brick to be piled. The openings, *f*, *g*, will enable the operator to rake the burning fuel down and prevent it from being piled up under the fuel openings *e*, *e'*. Lastly, by 15 locating the draft openings, *m*, in the partition walls, *b*, the "water-smoke" developed by the burning of the green brick will be drawn directly out of the chamber instead of being required to traverse the whole 20 chamber, as is the case in present structures, where the draft openings are in the floor of the end walls. Under the latter condition, the "water-smoke" condenses and discolors the bricks, which I avoid by taking 25 the smoke directly out of the chamber before it has time to condense.

I claim:

1. In a brick kiln of the character described comprising a series of adjacent 30 chambers and partitions separating such chambers, the combination of draft flues extending longitudinally in the partitions and having inlets from the related chamber, a main smoke passageway extending lengthwise of the kiln, branch passageways in the partitions, said branch passageways connecting the draft flues with said main smoke passageway, dampers controlling those ends of said branch-passageways connecting 35 40 with said draft flues, and auxiliary inlet passageways connecting the interior of the chambers with said branch passageways in the partition.

2. In a brick kiln of the character described comprising a series of adjacent 45 chambers and partitions separating such chambers, the combination of fuel openings extending through the roof of the kiln and located alongside the partitions, covers for 50 such fuel openings, longitudinal draft-flues in the partitions, the respective draft flues

being in communication with the related of said fuel openings, a main smoke passageway extending lengthwise of the kiln, branch passageways in the partitions connecting the draft-flues with said main smoke passageway, and dampers controlling those ends of said branch passageways connecting with said draft-flues.

3. In a brick kiln of the character de- 60 scribed comprising a series of adjacent chambers and partitions separating such chambers, the combination of fuel openings extending through the roof of the kiln and located alongside the partitions, covers for 65 such fuel openings, longitudinal draft-flues in the partitions, the respective draft flues being in communication with the related of said fuel openings, a main smoke passageway extending lengthwise of the kiln, 70 branch passageways in the partitions connecting the draft-flues with said main smoke passageway, dampers controlling those ends of said branch passageways connecting with said draft-flues, and auxiliary inlet passageways connecting the interiors of the chambers with said branch passageways in the 75 partition.

4. In a continuous brick kiln comprising a plurality of arched chambers separated by 80 partition walls and connected in series by openings arranged in the partition walls in zig-zag order, entrance doors in the end walls of each chamber, fuel-supply openings in the ceilings of the chambers, and fuel 85 control openings in the end walls of each chamber.

5. In a continuous brick kiln comprising a plurality of arched chambers separated by 90 partition walls and connected in series by openings arranged in the partition walls in zig-zag order, entrance doors in the end walls of each chamber, fuel-supply openings in the ceilings of the chambers, fuel control 95 openings in the end walls of each chamber, and said fuel control openings being located in the same vertical planes as the fuel supply openings.

ALOIS KLOSE.
